UNITED STATES PATENT OFFICE

RUDOLF VÖLZING, OF BERLIN-SIEMENSSSTADT, GERMANY, ASSIGNOR TO WESTINGHOUSE ELECTRIC & MANUFACTURING COMPANY, A CORPORATION OF PENNSYLVANIA

SELECTIVE PROTECTIVE SYSTEM FOR MORE THAN TWO PARALLEL FEEDERS

Application filed December 2, 1926, Serial No. 152,235, and in Germany December 4, 1925.

My invention relates to a selective protective system for more than two parallel feeders.

There are already known systems for the 5 selective or discriminative isolation of defective feeder for any number of parallel feeders, in which directional relays are connected between the center and the corner points of a polygon formed by the secondaries of current transformers placed in the 10 individual feeders to be protected.

My invention consists of a system or means 15 for supplying to such directional relays connected in the known manner, the voltage without employing special voltage transformers.

With this end in view, according to my invention, bifilar choke coils or reactors are placed between any two transformers in such 20 a manner that their centers form the corner points of the polygon with which are connected the current coils of the directional relays. The voltage coils of each directional relay are connected with the two ends of the 25 corresponding choke coils.

In the drawing affixed hereto:

Fig. 1 is a schematic showing of my invention as applied to three parallel feeders, one phase only of which is shown,

30 Fig. 2 is a schematic showing of a system for ensuring the response of the protective means of the remaining feeders after a defective feeder has been isolated, and

35 Fig. 3 is a schematic showing of a system for ensuring the response of the protective means in the event of a ground.

Referring to Fig. 1 of the drawing *a, b, c* are the feeders to be protected and *11, 12, 13* the current transformers. Between the secondaries of said current transformers are connected the bifilar choke coils or reactors *14, 15 and 16*. The effect of the bifilar choke coils may be improved by the loading resistors *30, 31 and 32*. The directional relays *d, e and f* are of the usual watt-meter type employing current windings *17, 18 and 19*, and voltage windings *20, 21 and 22*, respectively, to control the operation of contacts in accordance with the magnitude and direction of the energization thereof.

Under normal circuit conditions, the magnitudes of the currents traversing the two windings of the bifilar coils *14, 15, 16* are equal and opposed so that the voltage windings *20, 21 and 22* are not energized. Upon 55 the occurrence of a fault however, such as indicated at *23* in the feeder *b*, the energization of the two windings of the coil *15* is altered with respect to each other, and a potential difference occurs across the coil which energizes the voltage winding *21* of relay *c*. The 60 directional relay *c* then becomes operative and closes the tripping circuit through the solenoid *28*, which attracts its plunger and opens the switch *25* in the feeder *b*. 65

In order to ensure the correct response of the protective means or system for the remaining feeders, subsequent to the isolation of a defective feeder, it is necessary that the parts of the protective means related to the defective feeder be disconnected or short-circuited. It is therefore in the case under 70 consideration necessary to bridge the secondary of the current transformer *12* and the bifilar choke coil *15* by a short circuit connection and also to break the connection between the neutral point of the bifilar choke coil *15* and the current coil *18* of the relay *c*. 75

This may be effected by providing each of the switches *24, 25 and 26* with a contact member which in the closed position of the switch bridges two contacts placed in the connection of the respective bifilar choke coil to the corresponding current coil of the relay, and which when the switch is opened bridges 80 two contacts, one of which is connected with the beginning of the secondary of the corresponding current transformer and the other with the end of the corresponding bifilar choke coil or reactor. 85

Such an arrangement is illustrated in Fig. 2 of the drawing.

Referring to this figure, *25* is the switch 90 operatively connected in the feeder *b*, the movable part of which is provided with the contact member *34*. This contact member closes the pair of contacts *35* when the switch is opened. One of said contacts is connected with the terminal at the beginning of the secondary of the current transformer *12* in the 95

feeder *b* and the other of said contacts is connected with the terminal at the end of the bifilar choke coil 15 belonging to the relay *e*, which controls the switch 25. When the switch 25 is closed the contact member 34 bridges the two contacts 36, placed in the connection between the neutral point of the bifilar choke coil 15 and the coil 18 of the relay *e*.

In order to make sure that the protective system also responds correctly in case of a ground, current transformers must be placed in all phase conductors of a feeder. If the system should become operative only in the case of a short circuit between any two conductors, the current transformer in one conductor of a complete polyphase line may be omitted. In a three-phase system two transformers will therefore suffice for each three-phase feeder. The two transformers of two phases may then in known manner be connected in opposition, as diagrammatically illustrated in Fig. 3 of the drawing. In this way a substantially simpler arrangement of the circuits is obtained. In this figure 41, 42 and 43 are the three-phase busbars and 44, 45, 46 and 47, 48, 49 and 50, 51, 52 the three outgoing parallel three-phase feeders. In two phases of each of these feeders viz, in 44 and 45, as well as 47 and 48 and likewise 50 and 51 are placed current transformers. The two secondaries of these current transformers are connected in opposition and these groups are connected in series across the bifilar choke coils 53, 54 and 55. With the neutral points of these three bifilar choke coils or reactors are connected the current coils of the three relays 56, 57 and 58 and the second coils of each relay are connected with the ends of the bifilar coils, as described above.

The operation of the system is substantially the same as in the case of Fig. 1, except that it is applied to a three-phase system, and is obvious in view of the above described operation.

Various modifications and changes may be made without departing from the spirit and the scope of the invention, and I desire, therefore, that only such limitations shall be placed thereon as are imposed by the prior art.

I claim as my invention:—

1. In a protective system, the combination with a plurality of parallel feeders, current transformers operatively associated with said feeders, a bifilar choke coil connected in circuit with the secondary windings of said transformers, and means for effecting the disconnection of a feeder in response to a fault therein including a power-directional relay having a current and a voltage winding, means for energizing said current winding in accordance with the current traversing said transformers, and means for energizing

said voltage winding in accordance with the potential drop across the bifilar choke coil.

2. In a protective system, the combination with a plurality of parallel feeders, current transformers operatively associated therewith, a loop circuit including the secondaries of said transformers, bifilar choke coils connected in series in said circuit, and means for effecting the disconnection of a feeder in response to the occurrence of a fault therein comprising power-directional relays having current and voltage windings, said current windings having one of the terminals thereof connected to the midpoint of said choke coil and the other terminals connected to each other, and said voltage windings connected across the terminals of said choke coil.

3. In a protective system, the combination with a plurality of parallel feeders, current transformers operatively associated therewith, a loop circuit including the secondaries of said transformers, bifilar choke coils connected in series in said circuit, and means for effecting the disconnection of a feeder in response to the occurrence of a fault therein comprising power-directional relays having current and voltage windings, said current windings having one of the terminals thereof connected to the midpoint of said choke coil and the other terminals connected to each other, and said voltage windings connected across the terminals of said choke coil, and means operative upon the disconnection of a defective feeder for rendering ineffective the transformer secondary and bifilar choke coil associated therewith.

In testimony whereof, I have hereunto subscribed my name this 15th day of November, 1926.

RUDOLF VÖLZING.
